UNITED STATES PATENT OFFICE.

CHARLES J. BOGERT, OF BROOKLYN, NEW YORK, ASSIGNOR TO THE J. L. MOTT IRON WORKS, OF NEW YORK, N. Y., A CORPORATION OF NEW YORK.

DESIGN FOR FLOOR OR WALL COVERING.

SPECIFICATION forming part of Design No. 36,140, dated November 11, 1902.

Application filed May 1, 1902. Serial No. 105,565. Term of patent 14 years.

To all whom it may concern:

Be it known that I, CHARLES J. BOGERT, a citizen of the United States, residing in the city of New York, borough of Brooklyn, in the county of Kings and State of New York, have invented and produced a new, original, and ornamental Design for Floor or Wall Covering, of which the following is a specification, reference being had to the accompanying drawing, forming part thereof.

The drawing is a plan view of a section of mosaic floor or wall covering involving my design.

My ornamental mosaic floor or wall covering is composed of a plurality of tiles of uniform shape, the design being formed by the meeting edges of the tiles in straight lines crossing at a right angle and in intermediate segments of circles, all as illustrated in the drawing, the said pattern being made up of assembled tiles, each composed of a figure the basis of which is two squares having a common diagonal axis and touching at the corner of each, said figure being modified by having

removed from the outermost corner of each square a segmental portion having a radius equal to half the length of a side of the square and having added thereto within the angles between the squares corresponding segmental portions. The ends of the tiles at D are thus of concavely-curved outline, while the central portions A of the sides are of a convexly-curved outline, the halves B and C of each side of the squares farthest removed from their common diagonal being left undis- turbed.

Having described my design, what I claim, and desire to secure by Letters Patent, is—

The ornamental design for floor or wall covering as herein shown and described. 40

In testimony whereof I have signed my name to this specification, in the presence of two subscribing witnesses, this 29th day of April, 1902.

CHAS. J. BOGERT.
